(57) **CLAIM**

The ornamental design for a truss frame member for a modular building, as shown and described.

DESCRIPTION

FIG. 1 is a first perspective view of a truss frame member for a modular building showing my new design;
FIG. 2 is a second perspective view of the frame member of FIG. 1.

FIG. 3 is a front view of the frame member of FIG. 1.

FIG. 4 is a rear view of the frame member of FIG. 1.

FIG. 5 is a left side view of the frame member of FIG. 1.

FIG. 6 is a right side view of the frame member of FIG. 1.

FIG. 7 is a top view of the frame member of FIG. 1; and,

FIG. 8 is a bottom view of the frame member of FIG. 1.

The broken lines shown herein are for illustrative purposes and form no part of the claimed design.
